CLAIM

The ornamental design for an accessory for a foulard, as shown and described.

DESCRIPTION

FIG. 1 is a front elevational view of an accessory for a foulard according to a third embodiment;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view of the front and right side thereof; and,

FIG. 8 is a front elevational view showing the intended use of the accessory for a foulard.

The dashed lines on the surface of the article represent stitching.
